UNITED STATES PATENT OFFICE.

HENRY YOUNG GARRETT, OF ATLANTA, GEORGIA.

ADJUSTABLE SHADE PROTECTOR.

Application filed June 5, 1922. Serial No. 565,921.

To all whom it may concern:

Be it known that I, HENRY YOUNG GARRETT, a citizen of the United States, residing at Atlanta, in the county of Fulton and State of Georgia, have invented new and useful Improvements in Adjustable Shade Protectors, of which the following is a specification.

This invention has reference to an adjustable window-shade and provides an attachment designed to raise and lower the shade to allow light and ventilation at the top of the window and to permit the lowering of the upper sash without interference from the shade.

The invention further provides an adjustable shade protector and carrier which is adjustable to fit any window and which serves to protect the shade from dust or moisture when the window is opened from the top.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Figure 1 is an elevation of a window casing with the attachment in place thereon;

Figure 2 is a similar view showing a modification of the invention; and

Figure 3 is a detailed view of one end of the shade carrier, disclosing the bracket for supporting the shade.

Describing the invention in detail, 10 designates the window casing to which the attachment is applied, the same comprising a cylindrical tube or casing 11 which is split longitudinally, as at 12, to permit of expansion over the rolled up part of shade 13 and 45 is preferably formed of telescoped sections which are adjustable to fit any size window. This tube provides a protector for the shade, and has fastened thereto at each end a bracket 14, having a depending portion 15 which 50 supports one end of shade roller 16, and an outstanding portion 17 which engages a guide wire 18. Guide wires 18 are connected with the window casing at the top and bottom by screw eyes 19 and are stretched taut 55 in order that the protector and shade may be held to the casing by the slide portions

17, which slide portions 17 are provided with fingers 20 defining a slot 21 and having overlapping ends 22 between which the guide wires pass when entering the slots, 60 the said fingers being spaced horizontally from one another, as shown, to permit the wire to pass therebetween when the attachment is turned at the proper angle. The depending portion 15 of the brackets are provided, respectively, with a slot and an opening to support the ends of the shade roller 65 in the usual manner.

The shade and protector are suspended by flexible members 23, which wind around 70 spools 24 carried by a rotatable rod disposed across the top of the window casing. This rod comprises an intermediate section 25 in which are telescoped the outer spool-carrying sections 26 and 27, the latter being supported at their outer ends in brackets 28 on the casing. Set screws 29 are provided on section 25 for holding the parts in adjusted relation. Section 26 has a 80 sprocket 30 fixed thereon, around which passes an endless operating chain 31, the lower end of the chain passing around a drive sprocket 32. Drive sprocket 32 is mounted in a bracket 33 fastened to the side of the casing as shown at 34, and suitable 85 operating means are provided for turning the sprocket to propel the chain, whereby the flexible members 23 are caused to wind or unwind from the spools 24 for raising or lowering the shade. It will thus be 90 seen that the shade and protector may be moved to any desired position along the guides and, hence, may be lowered below the top of the window to obtain light or ventilation, the protector serving to shield the 95 shade from dust or moisture when the window is opened at the top.

In the modification shown in Figure 2, the protector and shade is raised and lowered by means of a counterbalance weight 35 which is attached to the protector by two cords 36 extending from the weight up through screw eyes 19 to each end of the protector where they are attached to shade brackets 14. By merely raising or lowering the weight, the position of the protector and shade may be varied to any extent. If desired, the attachment may be used without the counterbalance weight in which event the end of the cord would be engaged around a catch 37 fastened to one side of the window casing, and, likewise, a wooden

2
bar may be substituted for the protector tube, thus very materially reducing the cost of the attachment.

The construction of the device is such that the whole attachment may be taken down for any purpose by merely unscrewing screw-eyes 19, or the protector and shade may be removed intact from the guides by disengaging the spring fingers from the 10 guide wires, the opening in the protector enabling the shade to be conveniently removed therefrom or replaced therein at any time. Consequently, repairs may be quickly and expeditiously made.

15 From the foregoing it is thought that the construction and operation of the invention can be readily understood and that further detailed description is not required.

In practice, I have found that the form 20 of my invention illustrated in the accompanying drawings and referred to in the above description as the preferred embodiment, is the most efficient and practical; yet realizing the conditions concurrent with the 25 adoption of my device will necessarily vary, I desire to emphasize that various minor changes in details of construction, proportion and arrangement of parts, may be resorted to within the scope of the appended 30 claims without departing from or sacrificing any of the principles of this invention.

Having thus described my invention, and without enumerating variations and equivalents, what I desire protected by Letters 35 Patent is as set forth in the following claims:

1. An attachment of the character specified, comprising spaced guides, a shade shield of adjustable telescopic sections, positioned transversely between the said guides, a plate secured to each end of the shield extending beyond the ends thereof for engagement with the guides, a depending portion struck from the plate for holding the shade roller, and means for raising and lowering the said shield on the guides.

2. An attachment of the character specified, comprising spaced guides, a movable shade shield positioned transversely between the guides, means for moving the said shield, a shade bracket plate at each end of

the shield extending beyond the ends thereof for removable engagement with the guides, and a depending portion struck from the plate for holding the shade roller. 55

3. An attachment of the character specified, comprising spaced guides, a shade shield and protector consisting of a tube for embracing the rolled up part of the shade, said shield and protector having a 60 plate secured to and extending beyond each end thereof for sliding engagement with the guides, a depending portion struck from the plate for holding the shade roller, and means for raising and lowering the said 65 shield and protector between the guides.

4. An attachment of the character specified, comprising spaced guides, a shade shield and protector positioned between the said guides and consisting of a tube of relatively adjustable telescopic sections presenting a longitudinally extending slot through which the rolled up part of the shade is adapted to pass, said shield having plates at each end with depending portions struck 75 therefrom for engaging the ends of the tube, said plates extending outwardly from opposite ends of the shield to engage the said guides, and means for raising and lowering the said shield between the said 80 guides.

5. An attachment of the character specified comprising spaced guides, a shade shield of adjustable telescopic sections positioned transversely between the said guides, embodying a horizontal top section for securing to the shield, a downwardly and right angularly bent section integral with the top section and formed with means to engage one end of the shade, a guide engaging section likewise integral with the top section projecting in offset relation from the outer end thereof, and means for raising and lowering the said shield on the 90 guides. 95

This 2nd day of June, 1922.

HENRY YOUNG GARRETT.
